A. THOMPSON

BLOWER NOZZLE AND EXHAUST SPREADER

Filed March 1, 1924

UNITED STATES PATENT OFFICE.

ANDREW THOMPSON, OF BIRMINGHAM, ALABAMA.

BLOWER NOZZLE AND EXHAUST SPREADER.

Application filed March 1, 1924. Serial No. 696,404.

To all whom it may concern:

Be it known that I, ANDREW THOMPSON, a citizen of the United States of America, residing at Birmingham, in the county of Jefferson and State of Alabama, have invented 5 certain new and useful Improvements in Blower Nozzles and Exhaust Spreaders, of which the following is a specification.

My invention relates to a combination 10 blower nozzle and exhaust spreader for locomotives.

In the present practice the locomotive nozzle is reduced in area so as to increase the velocity of the exhaust and intensify the 15 draft, but this causes back pressure and adversely affects the power of the locomotive.

According to my invention I utilize the blower nozzle to form a spreader for the locomotive exhaust whereby a freer exhaust 20 is had which attains the requisite velocity and is controlled so as to strike the stack walls where it will give the best draft.

Moreover, in my invention I can arrange the blower jet concentric with the exhaust 25 nozzle and the stack where it will act most efficiently and I design it to spread the live steam jet like it will spread the exhaust steam jet, thus causing both jets to act with maximum efficiency in the stack.

30 My invention also contemplates the mounting of the blower nozzle on a spider interposed between the exhaust nozzle body and its tip. By adjustably mounting the blower nozzle on the spider I can regulate 35 the spread of the exhaust and by providing an adjustable spreader for the blower jet I can regulate that, so that the most efficient action can be obtained from both nozzles.

40 My invention further comprises the novel details of construction and arrangements of parts, which in their preferred embodiment only are illustrated in the accompanying drawings, in which:—

Fig. 1 is a transverse cross-sectional view 45 through the locomotive smoke box showing the exhaust nozzle in cross section and the blower nozzle and spider in side elevation.

Fig. 2 is a vertical cross section through the blower nozzle.

50 Figs. 3 and 4 are plan views and half cross-sectional views through the blower nozzle spider.

Similar reference numerals refer to similar parts throughout the drawings.

55 According to the preferred embodiment of my invention illustrated in the drawings, I

show conventionally in cross section the smoke box 1 of a locomotive having a stack 2 and an exhaust nozzle comprising a body 3 and a nozzle tip 4, the body and tip being 60 provided with contracting bores and being flanged so as to be bolted together in accordance with existing practice.

My invention consists essentially in a blower nozzle having an upwardly flaring 65 body 5, its lower end being reduced and threaded at 6 so as to be screwed into a threaded socket 7 in the diametric cross web 8 of a spider which has an annular body portion 9 shouldered to fit between the exhaust nozzle body 3 and tip 4 and to be held 70 in position by the connections (not shown) which secure the tip to the body. Live steam from the boiler is supplied by a pipe 10 to a nipple 11 which has communication 75 through a passage 12 in one side of the cross web of the spider to the bottom of the threaded socket through which the steam enters the bore 13 in the nozzle 5. A deep counter-sunk recess or chamber 14 is formed in 80 the upper end of the nozzle body 5 concentric therewith and at the bottom of the chamber a threaded socket 15 is provided which receives the lower threaded end 16 of a spreader plug 17, which end has a bore 85 corresponding with the bore 13. The upper end of the plug flares so as to spread the live steam flowing up through the bore 13 and outwardly from the plug bore through ports 18 into the chamber 14 surrounding the 90 spreader and thence outwardly between the spreader and the top of the nozzle. The tip of the nozzle has a flaring wall 19 parallel with the spreader wall and the two will deliver a divergent or spreading annular jet 95 of live steam. By screwing the plug more or less into the socket 15 the extent of the spread can be regulated so as to strike the walls of the stack 2 at a point where the most efficient draft will be induced. Washers 100 can be dropped into the socket 15 in order to regulate these adjustments if they be desired. In the same manner washers can be interposed between the lower end of the blower nozzle body 5 and the spider so 105 as to adjust the position vertically of the spreader nozzle relative to the tip 4 and thus control the spread of the exhaust steam so as to make it also strike the stack 2 at the critical point for securing the most effective draft. I prefer however to use a set screw 20 in the web 8 which will engage in a

slot 21 formed in the threaded shank 6 of the nozzle. This gives a less flexible adjustment but holds the parts positively in adjusted positions throughout the range of 5 adjustment usually required.

The cross web 8 of the spider is made narrow in cross section and tapered to a sharp edge above and below so as to form as small an obstruction as possible to the flow of the 10 exhaust steam. In its preferred form the greatest diameter of the nozzle 5 comes below its top edge in a position where it stands in the correct relation to the tip 4 to produce the spreading action desired. A tool grip 15 22 is on the upper closed end of the plug 17.

In practice, the spreader nozzle spider is mounted on the exhaust nozzle body 3 so that the blower nozzle 5 will stand concentric with the exhaust nozzle and the tip 4 after being set on the spider is bolted to the body 3 and the apparatus is ready for service. The spreading of both the exhaust and 20 live steam under control will give the most efficient exhaust. The device is readily applicable to existing locomotives and requires 25 no change in their standard parts.

Though I have described with great particularity the details of the embodiment of the invention herein shown, it is not to be 30 construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. A blower nozzle and exhaust spreader 40 for locomotives, comprising a nozzle having a live steam supply and a jet orifice formed between inner and outer members which flare upwardly, and means to mount the blower nozzle in the locomotive exhaust nozzle.

2. A blower nozzle and exhaust spreader 45 for locomotives, comprising a nozzle having a live steam supply and a jet orifice formed between inner and outer members which flare upwardly, and means to mount the blower nozzle with its outer flaring member 50 disposed concentrically in the locomotive exhaust nozzle.

3. The combination with a locomotive exhaust nozzle, of a blower nozzle mounted concentrically therein and having an inverted 55 conical body vertically, adjustably mounted within the contracted exhaust nozzle tip and adapted to spread the exhaust.

4. The combination with a locomotive exhaust nozzle comprising a body portion and 60 a tip, of a blower nozzle having a mounting spider adapted to be held between the exhaust nozzle body and its tip, said blower nozzle having an upwardly flaring body 65 adapted to spread the exhaust.

5. The combination with a locomotive exhaust nozzle comprising a body portion and a tip, of a blower nozzle having a mounting spider adapted to be held between the exhaust nozzle body and its tip, said blower 70 nozzle having an upwardly flaring body adapted to spread the exhaust, a live steam supply to the blower nozzle, and means on the blower nozzle to spread the live steam jet.

6. A locomotive blower having an enlarged chamber at the discharge end of the bore, and a spreader plug screwed into said chamber and having a bottom bore opening into the nozzle bore, and lateral steam outlet ports opening from its bore into said chamber, the plug forming an adjustable tapering spreader for the steam flowing through said chamber.

In testimony whereof I affix my signature,
ANDREW THOMPSON.
